UNITED STATES PATENT OFFICE.

FREDERICK H. GEORGE, OF MINNEAPOLIS, MINNESOTA, ASSIGNOR TO
W. S. NOTT COMPANY.

FRAME FOR STRETCHING LEATHER.

SPECIFICATION forming part of Letters Patent No. 680,855, dated August 20, 1901.

Application filed August 2, 1900. Serial No. 25,612. (No model.)

To all whom it may concern:

Be it known that I, FREDERICK H. GEORGE, a citizen of the United States, residing at Minneapolis, Minnesota, have invented certain 5 new and useful Improvements in Frames for Stretching Leather, of which the following is a specification.

My invention relates to the frames commonly employed in connection with stretching-machines for holding the leather both 10 while it is being subjected to tension by the machine and afterward while it is drying and until it has become set. Wooden frames are generally used for the purpose, and they are 15 objectionable for several reasons. If made sufficiently light for convenience in handling, they are liable to spring or break under the severe tension necessary to properly stretch thick leather, and when made of proper 20 strength for the work required they are heavy, inconvenient to handle, and occupy considerable space.

The principal object of my invention is to 25 avoid the objections to such wooden frames by constructing a more durable and more convenient frame composed mainly of metal.

My improvements are illustrated in the accompanying drawings, in which—

Figure 1 is a plan view of a stretcher-frame 30 and connections embodying my improvements. Fig. 2 is a transverse section, enlarged, of one of the side rails and a portion of the stretcher-head on the line *x* *x* of Fig. 1. Fig. 3 is a similar view on the line *y* *y* of Fig. 1, showing a portion of the head and the dog and toothed bar for locking it against return movement. Fig. 4 is a view similar to Fig. 3, but showing a variation in construction of the plate that supports the stretcher-head and carries the dogs. Figs. 5 and 6, respectively, show in plan view the same constructions as Figs. 3 and 4. Figs. 7 and 8 are plan views similar to Fig. 1, showing variations in the structure of the frame. Fig. 9 is 40 an end view of the frame from the right of Fig. 7. Fig. 10 is an enlarged detail of a portion of Fig. 9, and Fig. 11 is a like detail of a portion of Fig. 8.

In such drawings the side rails 1 of the frame 45 in the preferred form consist of metal, preferably steel, of channel or other suitable an-

gular shape, and, as shown, may comprise a web 2 and two flanges 3 at the same side. At one end these rails are connected by a bar or bars 4 and at the other end by the stationary 55 stretcher-head 5, which is secured to the flanges 3 by bolts 6. The slideable stretcher-head 7, which, like the stationary head 5, may be of wood, is held between upper and lower plates 8, that have flanges or projecting portions 9 extending within the flanges 3 of the rails for guiding the movements of the slideable head. The plates 8 may be separate pieces, as shown in Figs. 2, 3, and 5, or portions of a single casting, as indicated in Figs. 60 4 and 6.

Within the channels of the rails are secured toothed bars 10, which are engaged by dogs 11, carried by the head 7. The dogs are pivoted between studs 12 on plates 13 at the inner edges of the head and have handles 14 extending inward from the studs for turning the dogs on their pivots to release them from the teeth of the bars. Springs 15, which may be seated in sockets 16 in the head 7, have 70 heads or guides 15^a, which bear against the handles 14 to hold the dogs in engagement until released by pressure on the handles.

In the modifications illustrated in Figs. 7 to 11 the side rails 17 of the frame are shown 80 as consisting of metal tubes. In Fig. 7 they are shown to be united at one end by a cross-rail 18, also of tubing, by means of elbows 19 and at the other end by a hollow cross-rail 20 by means of elbows 21, extending upward 85 from the side rails. The latter cross-rail is elevated above the frame sides to make room for the stretching-machine connections. The fixed stretcher-head 5 is secured to the cross-rail 18 by eyebolts 22, the rail being passed 90 through the eyes and the bolts through the head 5 and held by nuts 23. On the inner edge of the head are plates 24, that are secured thereon by the bolts 22 and screw-bolts 25, and the projecting ends 26 of the 95 plate are suitably notched to partially span the side rails to prevent the head 5 from up-and-down movement. The slideable stretcher-head 7 has its outer edges supported and guided by similar plates 24, and on its inner edge are plates 27, having similar guiding ends 26, engaging the rails 17. The 100

latter plates are secured by short screw-bolts 25 and by bolts 28, which extend through the head and have eyes 29 at their outer ends for making connections with the stretching mechanism. The head 7 is thus adapted to move freely lengthwise of the side rails.

On the inner surfaces of the side rails are toothed bars 10, with which the dogs 11 engage, the construction and operation being the same as heretofore described. The laterally-projecting portions of the plates 24 and 27 are recessed, as shown at 30, to provide free spaces for the bars 10, so that the slidable head cannot come in contact with the bars 15 while in operation.

The construction of the frame itself is somewhat varied in the modification shown in Figs. 8 and 11. The end rails are dispensed with and the stretcher-heads are utilized for 20 suitably connecting the side rails. On the outer edge of the stationary head 5 are plates 31, having screw-threaded sockets in their enlarged outer portions 32 for receiving the ends of the side rails, and on the inner edge 25 of the head are plates 33, having collars 34 around the rails, and bolts 35 are passed through the plates 31 and 33 and the head 5 to hold the parts firmly in place. On the edges of the movable head 7 are plates 36 and 37, 30 provided with collars 38, loosely encircling the side rails and recesses 39, providing suitable spaces for the toothed bars. The plates 36 and 37 have flanges 40, which overlap the corners of the head 7 to strengthen the construction. The plates and head are secured 35 together and held in place by bolts 25 and 28, the latter having eyes 29. The ends of the side rails have caps 41 to protect and strengthen them.

40 In use the ends of a side or other division of leather are secured to the stretcher-heads 5 and 7 in any suitable way, and the frame is supported on a table or otherwise, with the ends of the side rails against the abutments 45 42 of a stretching-machine. The eyes 29 on the sliding head are then connected by rods

43 to the cross-head or other proper part of the stretching mechanism and power applied thereto. As the sliding head is advanced the dogs 11 engage the teeth of the bars 10 50 and when the head is disconnected from the power mechanism hold it from return movement. The dogs may be disengaged when desired by pressure on their spring-actuated handles.

Having described my invention, what I claim is—

1. A leather-stretching frame, consisting of metal side rails of channel-bar form, a cross-bar connecting one of the ends thereof, a stationary stretcher-head connecting the other end, a movable stretcher-head having upper and lower flanges at its ends extending within the channels of said rails for guiding its movements and having means for connecting it to a stretching-machine, rows of ratchet-teeth provided in the channels of the side rails, dogs carried by the movable head for engaging said teeth to prevent backward movement of the head, and springs for actuating the dogs, substantially as set forth.

2. A leather-stretching frame, consisting of metal side rails of channel-bar form, a cross-bar connecting one of the ends thereof, a stationary stretcher-head connecting the other end, a movable stretcher-head having upper and lower flanges at its ends extending within the channels of said rails for guiding its movements and having means for connecting it to a stretching-machine, rows of ratchet-teeth provided in the channels of the side rails, dogs pivoted to studs on the movable head and having handles for operating them, and springs engaging said handles for holding the dogs normally in engagement with said teeth, substantially as set forth.

In testimony whereof I have hereunto set my hand this 24th day of July, 1900.

FREDERICK H. GEORGE.

In presence of—

A. L. WHELAN,
P. H. GUNCKEL.
